UNITED STATES PATENT OFFICE.

PHILIP W. MOORE, OF EVANSTON, ILLINOIS, ASSIGNOR TO THE P & M COMPANY, OF CHICAGO, ILLINOIS, A CORPORATION OF ILLINOIS.

RAIL-ANCHOR.

1,159,065.

Specification of Letters Patent.

Patented Nov. 2, 1915.

Application filed December 30, 1914. Serial No. 879,711.

To all whom it may concern:

Be it known that I, PHILIP W. MOORE, a citizen of the United States, residing at Evanston, in the county of Cook and State 5 of Illinois, have invented certain new and useful Improvements in Rail-Anchors, of which the following is a specification.

My invention relates to improvements in rail anchors, that is, devices for preventing 10 the longitudinal creep of railroad rails.

One of the principal objects of the invention is to provide a rail anchor suitable for attachment to a rail where the free space at one edge of the rail base is limited, for example, where a guard rail lies close to the 15 rail to be anchored.

A further object of the invention is to provide a rail anchor of the wedge type in which the movable element is so related to 20 the stationary element that, in the application of the device to a rail, particularly a rail having a guard rail near by, the movable element may be driven toward the tie by striking it first at one end and then at 25 the other so that if a blow on one end twists or skews either part of the anchor on the rail base the parts may be straightened out by striking the other end of the driven member. It will be understood that the effectiveness and stability of the hold which a 30 device of the wedge type takes on the rail would be seriously impaired, if not destroyed, if the parts, or either of them, were twisted so that the wedges did not bear flatly 35 or squarely one against the other.

A further object of the invention is to provide a rail anchor of this type which will be light and strong and which, because of the large aggregate frictional area between 40 the parts of the anchor and because of the character of the engagement between said parts, will take and maintain a very firm and reliable hold on the rail capable of 45 withstanding vibration and other forces tending to destroy such hold.

Certain features of the present invention, broadly considered, are claimed in my co-pending application Serial No. 879,710, filed December 30, 1914. So far as the line of division 50 between these applications is concerned the common subject matter is intended to be covered in the other application.

The invention is illustrated, in a pre-

ferred embodiment, in the accompanying drawings wherein—

Figure 1 is an elevation of the device shown as applied to a rail standing in proximity to a guard rail; the two rails being shown in section; Fig. 2, a sectional plan taken on line 2—2 of Fig. 1; Fig. 3, a vertical section on line 3—3 of Fig. 2, and Figs. 4 and 5 are views, in perspective, of the two elements of the anchor.

Like characters of reference designate like parts in the several figures of the drawings.

Referring to the drawings, A designates a railroad rail, B one of the cross ties supporting the same, and C a guard rail, the flange D of which is cut off on one side so as to bring the heads of the rails close together in the usual manner.

The rail anchor of my invention consists, in the embodiment of the invention shown of a stationary element E (Fig. 4) and a movable element F. The stationary element is formed with a tie abutting plate G and with a jaw H, the latter adapted to extend around one edge of the base flange I of the rail. The movable element is formed with a jaw J adapted to engage the opposite edge of the rail base I, the jaw being of such configuration that it will enter the narrow space between the base flanges D and I. At the same end the movable element is formed with a tapered or wedging rib K preferably formed below the level of the under surfaces of rails A and C. At the other end the movable element has a jaw L adapted to extend around the jaw H of the stationary element. The surface l defining the interior of the jaw L is flared in the direction toward the tie and the coengaging outer surface h of jaw H has a corresponding contour whereby a wedging action is produced between the jaws when the movable element is driven toward the tie.

It will be understood that while the arrangement of the overlapping jaws H and L is preferred, any other suitable wedging engagement between the members of the anchor at this end of the device might be employed. The stationary member E is formed at the end opposite jaw H with a hook M, the interior surface m of which has the general configuration of the wedge K

so that a wedging action is produced at this end of the device when the movable element is driven toward the tie. These two wedging movements are on substantially parallel lines, with the result that when the free member F is driven toward the tie a very firm and intimate engagement is effected between the parts of the anchor. The hook M, it will be seen, is below the level of the upper face of the tie so that if the anchor is used upon a rail having a guard rail close to it, although obviously the device might be used upon any rail, whether in this situation or not, the wedging members at this end of the device may lie beneath the base flange of such guard rail. In applying the device it is possible, nevertheless, to strike the driven member at each end so that if a blow on one end twists either member the latter may be straightened out by a blow delivered against the other end of the driven member.

I do not claim herein, broadly, the provision of one member of a rail anchor of the wedge type with a wedge-shaped rib outstanding from the rail base engaging jaw which is engaged by a hook on the other member of the device, as this construction is claimed in my co-pending application Serial No. 879,712, filed December 30, 1914.

I claim:

1. A rail anchor comprising two co-engaging elements which together embrace the base flange of the rail to which the device is applied, one of said elements being formed with a tie abutting flange and each element adapted to engage the other at each end thereof, the engaging parts at one end of the device being below the level of the under surface of the base of said rail.

2. A rail anchor comprising two co-engaging elements which together embrace the base flange of the rail to which the device is applied, one of said elements being formed with a tie abutting flange and each element adapted to engage the other at each end thereof with a wedging engagement, the engaging parts at one end of the device being below the level of the under surface of the base of said rail.

3. A rail anchor comprising two co-engaging elements which together embrace the base flange of the rail to which the device is applied, one of said elements being provided with a tie abutting flange and said elements being formed on opposite ends with jaws which, in each instance, extend around the end of the other element, one of said jaws being below the level of the under surface of the base flange of said rail.

4. A rail anchor comprising two co-engaging elements which together embrace the base flange of the rail, to which the device is applied, one of said elements being provided with a tie abutting flange and said

elements being formed on opposite ends with jaws which, in each instance, extend around and have a wedging engagement upon the end of the other element, one of said jaws being below the level of the under surface of the base flange of said rail.

5. A rail anchor comprising two co-engaging elements which together embrace the base flange of the rail to which the device is applied, one of said elements being provided with a tie abutting flange and said elements being formed with jaws one on each member engaging opposite edges of the rail base and with jaws one on each member which extend around, in each instance, the end of the other element, one of said last named jaws being below the level of the under surface of the base flange of said rail.

6. A rail anchor comprising two co-engaging elements which together embrace the base flange of the rail to which the device is applied, one of said elements being provided with a tie abutting flange and said elements being formed with jaws one on each member engaging opposite edges of the rail base and with jaws one on each member which extend around and having a wedging action upon the end of the other element, one of said last named jaws being below the level of the under surface of the base flange of said rail.

7. A rail anchor comprising two co-engaging elements one element formed with a jaw engaging one edge of the base flange of the rail to which the device is applied, with a wedge-shaped rib on the end adjacent said jaw and with a jaw on the other end; the other element being formed with a jaw embraced by the last named jaw and intervening between the same and the rail base, and with a hook on the other end engaging the wedging rib on the first named element.

8. A rail anchor comprising two co-engaging elements, one element formed with a jaw engaging one edge of the base flange of the rail to which the device is applied, with a wedge-shaped rib on the end adjacent said jaw and with a jaw on the other end; the other element being formed with a jaw embraced by the last named jaw and intervening between the same and the rail base, with a hook on the other end engaging the wedging rib on the first named element, and with a tie abutting flange.

9. A rail anchor comprising two co-engaging elements, one element formed with a jaw engaging one edge of the base flange of the rail to which the device is applied, with a wedge-shaped rib on the end adjacent said jaw below the level of the rail base and with a jaw on the other end; the other element being formed with a jaw intervening between the last named jaw and the rail base, and with a hook on the other end engaging the wedging rib on the first named element.

10. A rail anchor comprising two co-engaging elements, one element formed with a jaw engaging one edge of the base flange of the rail to which the device is applied, with
 5 a wedge-shaped rib on the end adjacent said jaw below the level of the rail base and with a jaw on the other end; the other element being formed with a jaw intervening between the last named jaw and the rail base,
 10 and with a tie abutting flange on the other end engaging the wedging rib on the first named element.
11. A rail anchor comprising two co-engaging elements, one element formed with a
 15 jaw engaging one edge of the base flange of the rail to which the device is applied, with a wedge-shaped rib on the end adjacent said jaw and with a jaw on the other end; the other element being formed with a jaw em-
 20 braced by the last named jaw and intervening between the same and the rail base, and with a hook on the other end engaging the wedging rib on the first named element, said overlapping jaws having a wedging en-
 25 gagement along lines substantially parallel with the wedging engagement between said rib and hook.
12. A rail anchor comprising two co-engaging elements, one element formed with a
 30 jaw engaging one edge of the base flange of the rail to which the device is applied, with
- a wedge-shaped rib on the end adjacent said jaw below the level of the rail base and with a jaw on the other end; the other element being formed with a jaw intervening be-
 35 tween the last named jaw and the rail base, and with a hook on the other end engaging the wedge-shaped rib on the first named ele-
 40 ment, said overlapping jaws having a wedg-
 45 ing engagement along lines substantially parallel with the wedging engagement be-
 50 tween said rib and hook.
13. A rail anchor comprising two co-engaging elements, one element formed with a jaw engaging one edge of the base flange of the rail to which the device is applied, with a wedge-shaped rib on the end adjacent said jaw and with a jaw on the other end; the other element being formed with a jaw embr-
 55 aced by the last named jaw and intervening between the same and the rail base, with a hook on the other end engaging the wedge-shaped rib on the first named ele-
 60 ment, and with a tie abutting flange, said overlapping jaws having a wedging engage-
 65 ment along lines substantially parallel with the wedging engagement between said rib and hook.
